UNITED STATES PATENT OFFICE.

ALEXANDER CARNIE, OF NORTH BRANCH, MICHIGAN.

CALCINING-FURNACE.

1,158,372.

Specification of Letters Patent. Patented Oct. 26, 1915.

Substitute for application Serial No. 612,532, filed March 6, 1911. This application filed February 13, 1915.
Serial No. 7,964.

To all whom it may concern:

Be it known that I, ALEXANDER CARNIE, a subject of Great Britain, residing at North Branch, in the county of Lapeer and State 5 of Michigan, have invented certain new and useful Improvements in Calcining-Furnaces, of which the following is a specification.

My invention relates to improvements in 10 calcining and clinkering furnaces.

It is particularly adapted for calcining and clinkering the materials used in the manufacture of hydraulic cement, such as Portland cement.

One of the objects of my invention is to 15 provide an apparatus in which the cement making materials may be thoroughly combined and calcined and clinkered, and in which the calcined material will be produced 20 in comminuted form so as to be readily handled and ground.

Other objects of my invention are herein- 25 after fully described.

In an application filed by me March 6, 25 1911, having Serial Number 612,531, I have claimed the method herein described.

In the accompanying drawing which 30 illustrates the preferred form of my invention, there is shown a vertical sectional view of the apparatus.

The calcining and clinkering chamber 35 comprises, preferably, a vertical stack having an outer casing 1 enveloping a fire brick lining 2, the casing and fire brick being supported upon a base 3. The top of the stack is provided with a cap 4 provided with a central vertical opening in which is fitted the downwardly turned end of a horizontal conductor 5, which is connected to the bottom 40 of a hopper 6 into which are placed the materials to be calcined and clinkered and which are to form the cement.

Longitudinally through the conductor 5 extends a rotary shaft 7 provided in said 45 conductor 5 with a feed screw 8 which is adapted when rotated in the proper direction to force the cement materials from the hopper 6 through the conductor 5.

Extending through the stack below the 50 cap 4 is a rotary shaft 9 on which is secured a horizontal drum 10 provided with radial blades 11 located in the stack below the discharge end of the conductor 5. The drum 10 and blades 11 serve as a rotary device 55 for diffusing in the upper part of the stack

or calcining chamber, the materials to be calcined. The material to be calcined and clinkered is preferably in a finely powdered form, so that when the materials fall upon the rotary drum 10 they will be diffused and 60 will then fall slowly toward the bottom of the stack.

Any suitable means may be provided for 65 rotating the shaft 9. A shaft 21 has mounted on and rotative with it a worm 23 which meshes with a worm wheel 24 secured to the shaft 7. Thus by means of the mechanism just described, when the shaft 21 is rotated the screw 8 will be rotated. Any means may be provided for rotating the shaft 21. 70

To calcine and clinker the material while it is falling after its diffusion in the stack I provide a burner 25 which extends horizontally through the wall of the stack and has its discharge end extending upwardly 75 centrally in the stack and below the drum 10.

The inlet end of the burner outside of the stack is connected to one end of a horizontal conductor 26, the other end of which is connected to a blower 27 of any suitable type 80 having a horizontal driving shaft 28 which may be rotated by any suitable means.

Mounted on a frame 12 is a bin 32 adapted to contain fuel, such as fine coal or coal-dust. Connected at one of its ends to the lower 85 part of the bin 32 is a horizontal conductor 33, the other end of which is downwardly turned and is connected to the upper side of the conductor 26. Extending through said conductor 33 and through the lower 90 part of the bin 32 is a horizontal rotary shaft 34 on which is mounted a feed screw 35, which also extends into the bin 32. When the shaft 34 is turned in the proper direction, the feed screw 35 will force the 95 fuel from the bin 32 into the conductor 26, from which the fuel is blown by the air blast from the blower 27, into and through the burner 25.

To rotate the shaft 34 it has secured to it 100 a worm wheel 36, which meshes with a worm 37 secured to a rotary horizontal shaft 38, which may be rotated by any suitable means.

To protect the burner 25 from the heat, 105 it is preferably encircled by a casing 42. Between the casing 42 and burner 25 is a space 43, which is supplied with water by a conductor 44 connected to the lower end of a tank 45, which is mounted on the frame 110

12 and contains water. Also connected to the casing 42 and communicating with the space 43 is a conductor 46 which is connected to the tank 45 near the top thereof. By 5 means of the tank 45 and conductors 44 and 46, the space 43 is kept supplied with water. The burner 25 is preferably located between the drum 10 and the receiving end of a smoke outlet comprising a pipe 47, the 10 lower horizontal end of which is connected to the stack between the base 3 and the burner 25. The vertical portion of the pipe 47 may extend to the height required to effect the proper draft.

15 The upper side of the base 3 is hopper-shaped and has mounted in the lower part of its recessed upper side a horizontal rotary shaft 48 which extends through the base 3 and has mounted on it a feed screw 20 49, which extends into the hopper-shaped depression 50 of the base 3 and through a horizontal discharge opening communicating with said depressed portion 50.

In operating my invention, the shafts 21, 25 38, 48, 28, and 9 are rotated, thereby operating the screws 8, 35 and 49, the blower 27 and drum 10. The mixed fuel and air discharged from the burner 25 is ignited and the flame resulting therefrom will be blown 30 upwardly in the stack toward the drum 10. A down current will also be formed by the air pressure in the upper part of the stack, thus carrying downward and then outward and upward through the pipe 47 35 the gaseous products of combustion.

When the stack has become sufficiently heated, the material to be calcined and clinkered is placed in the hopper 6 from which it is carried by the screw 8 and discharged 40 into the stack upon the rotating drum 10, the blades of which diffuse the powdered cement materials, which in falling, are calcined and clinkered by the flame from the burner 25 and are deposited in 45 the form of small nodules or clinkers upon the base 3 and in the depression 50 thereof. The rotating screw 49 carries these nodules or clinkers out through the discharge opening in which is located the screw 49. These 50 nodules are then in convenient form for the succeeding grinding operation.

By reason of the upward blast from the burner 25, the finely powdered cement materials are thoroughly commingled and calcined and clinkered, and, as the calcination and clinkering occurs while the particles are suspended in the air or gaseous substances in the stack, the cement materials do not form into large masses which would 60 be difficult to break up, but form into nodules or clinkers of small size. These nodules or clinkers are readily removed from the stack by the screw 49.

I do not limit my invention to the structure illustrated and described, as various

modifications, within the scope of the appended claims, may be made without departing from the spirit of my invention.

What I claim is:—

1. A calcining and clinkering furnace 70 having a calcining and clinkering chamber comprising a vertical stack having no outlet near the top and having near the bottom an outlet for smoke and gas, means for discharging into the upper part of the 75 chamber in powdered form the material to be calcined and clinkered, the chamber being adapted to permit the material to fall freely toward the bottom of the chamber, and a burner in said chamber between the 80 outlet and the place of introduction of the material.

2. A calcining and clinkering chamber having no outlet near the top and having near the bottom an outlet for smoke and 85 gas, a conductor discharging into the upper part of said chamber, means for forcing the material to be calcined and clinkered in powdered form through said conductor into 90 said chamber, means in said chamber for diffusing the said material, the chamber being adapted to permit the diffused material to fall freely toward the bottom of the chamber, and a burner in said chamber for calcining and clinkering the material while 95 it is falling.

3. A calcining and clinkering chamber comprising a vertical stack having no outlet near the top and having a smoke outlet 100 near the bottom, means for discharging into the chamber at the upper end thereof material in powdered form to be calcined and clinkered, means in said chamber for diffusing in the upper part of the chamber 105 said material, the chamber being adapted to permit the diffused material to fall freely toward the bottom of the chamber, a burner in said chamber for heating the material while it is falling, and means for discharging the calcined and clinkered material from 110 the chamber.

4. A calcining and clinkering chamber comprising a stack having no outlet near the top and having a smoke outlet near the bottom, means for carrying into the chamber 115 material to be calcined and clinkered in powdered form and discharging said material near the top of said chamber, means in said chamber for diffusing the said material, the chamber being adapted to permit the diffused material to fall freely toward the bottom of the chamber after diffusion, a burner for calcining and clinkering the material while it is falling, the burner being located so as to discharge its flame above 120 the outlet and toward the diffusing means, and means for carrying from the chamber the calcined and clinkered material.

5. A calcining and clinkering chamber comprising a vertical stack having no out- 130

- let near the top and having near the bottom a smoke outlet, means for feeding into said stack in the upper part thereof material in powdered form to be calcined and clinkered, the chamber being adapted to permit the diffused material to fall freely toward the bottom of the chamber, and means for discharging upwardly in said chamber a flame in contact with the material while the material is falling. 5 of the chamber for diffusing therein the 30 said material, and means for discharging upwardly in said chamber between said outlet and said diffusing means burning fuel which contacts with the material while it is falling, and after its diffusion. 35
6. A calcining and clinkering chamber having no outlet near the top and having a smoke outlet near the bottom, means for feeding material to be calcined and clink- 8. A calcining and clinkering chamber 40 15 ered in powdered form into the upper part having no outlet near the top and having a smoke outlet near the bottom, means for feeding material to be calcined and clinkered in powdered form into the upper part of the chamber, means for diffusing the material in the chamber, the chamber being adapted to permit the diffused material to fall freely toward the bottom of the chamber, and means for discharging upwardly in the chamber a flame which contacts with the diffused material while the material is falling. 20 45 20 50
7. A calcining and clinkering chamber having no outlet near the top and having a smoke outlet near the bottom, means for feeding into the upper part of the chamber material to be calcined and clinkered in powdered form, means in the upper part

In testimony whereof I have signed my name to this specification in presence of two subscribing witnesses.

ALEXANDER CARNIE.
